UNITED STATES PATENT OFFICE.

ADOLPH W. SCHRAMM, OF RIVERTON, NEW JERSEY, AND EDWARD B. WILFORD, OF MERION, PENNSYLVANIA, ASSIGNORS TO ELECTRO DENTAL MANUFACTURING COMPANY, OF PHILADELPHIA, PENNSYLVANIA, A CORPORATION OF PENNSYLVANIA.

DESIGN FOR A SWITCHBOARD-MOUNTING.

43,725.

Specification for Design.

Patented Mar. 18, 1913.

Application filed December 4, 1911. Serial No. 663,932. Term of patent 14 years.

To all whom it may concern:

Be it known that we, ADOLPH W. SCHRAMM and EDWARD B. WILFORD, citizens of the United States, residing in Riverton, Burlington county, New Jersey, and Merion, Montgomery county, Pennsylvania, respectively, have invented a certain new, original, and ornamental Design for a Switchboard-Mounting, of which the following is a specification, reference being had to the accompanying drawing, forming part thereof, in which—

Figure 1, is a perspective view of our switchboard mounting, and Figs. 2 and 3, are respectively a side and an end elevation of the mounting shown in Fig. 1.

We claim:

The ornamental design for a switchboard mounting as shown.

ADOLPH W. SCHRAMM.
EDWARD B. WILFORD.

Witnesses:

WILLIAM E. BRADLEY,
Jos. H. KLEIN.
